UNITED STATES PATENT OFFICE

GEORGE HENRY ELWELL, OF NEW HAVEN, CONNECTICUT, ASSIGNOR TO THE GREIST MANUFACTURING COMPANY, OF NEW HAVEN, CONNECTICUT, A CORPORATION OF CONNECTICUT

ELECTRIC LAMP SOCKET

Application filed October 10, 1927. Serial No. 225,192.

The invention relates to improvements in electric lamp sockets adapted to receive an incandescent lamp bulb and to lock the same therein against theft. The art discloses varied forms of theft proof electric lamp sockets of which many require some special construction of the metal base of the lamp bulb, or the breaking of the lamp bulb upon its removal, but the invention herein disclosed adapts the improved lamp socket to receive and to lock therein the ordinary incandescent lamp bulb releasable only under certain conditions. The applicant is also aware that improvements in the art have already extended to electric lamp sockets of this character which include either a rotatable screw-shell adapted to be locked against rotation upon the authorized placing and removal of the lamp bulb, or a locking band or cover with an inturned flange to lockingly engage with the annular edge of the metal base of the lamp bulb. The rotatable screw-shell and the locking band both have their advantages, and it is the intention of this invention to so employ principles suggested, perhaps, by each in the new construction of a novel theft-proof electric lamp socket that will further develop the art in that direction, and therefore the objects of the invention are to provide an electric lamp socket carrying a rotatable member adapted to lockingly engage the annular edge of the metal base of an ordinary electric lamp bulb and rotate therewith until the bulb is fully in place within the screw-shell contact and then automatically become locked against reversed rotation; and to provide for the removal of the bulb only when the electric circuit embracing the particular fixture is opened by means of the throwing off the circuit switch.

The following is the description of an embodiment of the invention the construction of which may be varied within the scope of what may hereinafter be claimed without departing from the spirit or modifying any of the advantages of the invention. Reference being had to the accompanying drawing (one sheet) the Figure 1 is an upright elevation of an improved socket without a casing, but with a metal base of an electric

lamp bulb locked thereto; Figure 2 is a similar upright elevation but in a different rotary position and including the insulation lining illustrated in cross-section; Figure 3 is an upright elevation of the screw-shell and rotatable member in associated relation; and Figure 4 is a cross-sectional view of the socket at the line "4-4" of Figure 1, illustrating the rotatable member unlocking means.

Referring more particularly to the drawing, in which similar parts are similarly numbered, the screw-shell 1 is fixed to the body of insulation 2 in any desired manner. The rotatable locking member 3 is of such screw-shell formation as to adapt it for meshing its rolled-in thread with the exterior presentation of the rolled-in thread of the screw-shell 1, as best illustrated by Figure 3. The inner extremity of the rotatable locking member 3 is provided with an unthreaded annular portion 4 carrying the spring arm 5 inwardly presenting the catch 6 for locking engagement with an edge 7 bounding an opening 8 in an unthreaded portion 9 of the screw-shell 1. This opening 8 ordinarily exists in screw shell formation already known to the art, but if desired a special opening 8 may be provided for the purpose above explained. The outer extremity of the rotatable locking member 3 is so constructed as to assume the form of a series of spring arms, preferably more than two, each arm presenting an inturned flange portion 10, as best illustrated by Figure 3, for locking engagement with the annular edge 11 of the metal base 12 of an ordinary incandescent lamp, as illustrated in Figures 1 and 2. The unthreaded portion 4 of the rotatable member is provided, substantially diametrically opposite the catch 6 and the edge 7 in locked relation, with a small elongated perforation 13. A similar perforation in the unthreaded portion 9 of the screw-shell is made unnecessary by the usual opening therein corresponding with and located opposite the opening 8 and extending sufficiently to be used as illustrated by Figure 4 and as later explained. The floor 14 of the lamp receiving socket to which the shell 1 is rigidly secured is provided with the guide 15 to positively direct the course of a needle

16 inserted within the perforation 13, and a convenient way in which to construct this guide is by rolling it up out of the screw-shell bottom as illustrated by Figure 4. The course of the needle 16 as directed by the guide 15, an integral part of the screw-shell 1, insures the engagement of the needle with the contact 17 an integral part of the switch contact bar 21 depending therefrom, the other switch bar 19 depending from the center contact 20 and being parallel to and in spaced relation with the switch contact bar 21, as illustrated in dotted line by the Figure 1, and the catch 6 in locked position. It is obvious that when the rotatable member 3 is rotated upon the screw-shell to a degree greater than is illustrated by Figure 3 the lamp bulb may be inserted therein so that the inturned flange portion 10 may engage the edge 11 of the metal lamp base 12. The bulb may be screwed into the screw-shell as the rotatable member is turned therewith first by the hand and then carried by the grip of the spring arms around the annular edge 11 until the lamp is electrically connected and the spring catch 6 falls over the edge 7, as illustrated by Figure 1. The lamp bulb thereby becomes automatically locked within the electric lamp socket; for any attempted unauthorized removal thereof is prevented by the flange portions 10 blocking the displacement of the annular edge 11 of the lamp base and the inability of the rotatable locking member 3 to turn with the bulb by reason of its locked condition with the screw-shell as above explained. Any manipulation of the flanges in an attempt to release the lamp bulb is frustrated by the fact that these spring arms 5 are protected by the snug relation thereto of the insulation sleeve 18 illustrated by the Figure 2, associated with the electric lamp socket in a manner well-known to the art. The electric circuit switch, controlling the fixtures from one of which it is desired to remove a lamp bulb, must first be thrown off to open the circuit. The steel needle 16 extending through the insulation sleeve 18 which is then inserted into the perforation 13 and necessarily through the guide 15, an integral part of the screw-shell 1, and, contacting with the contact 17, finally engages the inner surface of the catch 6, enabling the pushing of the spring arm 5 sufficiently to disengage the catch 6 from the edge 7 while a reversed rotation of the lamp bulb carrying the rotatable member thus freed is then limited only by the needle 16 within the elongated perforation 13. The needle may immediately be withdrawn; for the continued rotation of the lamp bulb carries the rotatable member 3 with its catch 6, the latter immediately riding out of the plane of the opening 8. With the switch board locked up within an enclosure or located in a remote place and therefore not readily accessible to the unauthorized person

it makes it difficult, if not impossible, for an electric lamp bulb to be wrongfully removed; for any attempt to remove a lamp bulb locked within this improved socket without first having thrown off the general switch would endanger the manipulator should he thrust a needle into the perforation 13 while the screw-shell and the center lamp contact are electrically alive. By providing the guide 15 for the entrance therein of a fragile steel needle with which to release the catch 6, no substitute of insulation material, such as a toothpick, can be employed to defeat the purpose of this invention.

What I claim is:

1. An electric lamp socket comprising a screw-shell to receive the threaded base of a lamp, a second screw-shell threaded upon said first shell and carrying flanged portions for holding engagements with an annular edge of the threaded base, and means provided by both shells to lock the shells against relative reverse rotation.

2. An electric lamp socket comprising, a screw-shell to receive the threaded base of a lamp, said shell having an opening in its cylindrical wall, and a second screw-shell threaded upon the first shell and carrying flanged portions for holding engagements with an annular edge of the lamp base, and a catch member carried by the second shell for engagement within the opening to lock the shells against reverse rotation.

3. An electric lamp socket comprising a screw-shell to receive the threaded base of a lamp, said shell having oppositely positioned openings in its cylindrical wall, a second screw-shell threaded upon the first shell and carrying flanged portions for holding engagements with an annular edge of the lamp base, a catch member carried by the second shell for engagement within one of the openings to lock the shells against relative reverse rotation, and means provided by the socket to safely dislodge the catch member from its locking engagement only with the electric current cut off.

4. An electric lamp socket comprising a screw shell for receiving the threaded metal base of a lamp; a sleeve of insulation surrounding said screw-shell, the screw-shell having oppositely positioned openings in its cylindrical wall; contacts within the shell and insulated one from the other and from the shell, each contact having a fixed depending switch bar; a guide having a passage therethrough provided by the shell, the passage being aligned with one of the contacts; a second screw-shell threaded upon the first shell, the second shell having an elongated opening in its cylindrical wall to register with a screw-shell opening; flanged portions integrally provided by the second shell for holding engagements with an annular edge of an inserted metal base of a lamp, the sleeve

of insulation co-operating to maintain the holding engagements; a catch member carried by the second shell for engagement within one of the openings of the first shell to lock the shells against relative reverse rotation; and means to safely dislodge the catch from its engagement with the opening only with the electric current cut off, said means comprising a fragile needle adapted for entrance within openings of the second and first shells and into the guide passage to be thereby directed to and contacted with one of the contacts to establish between the shells and such contact a short circuit, the shells and such contact being within the electrical circuit.
